CLAIM

(21) Appl. No.: **29/102,738**

The ornamental design for fractional indicia on measuring implements, as shown.

(22) Filed: **Mar. 30, 1999**

DESCRIPTION

(63) Continuation-in-part of application No. 29/092,852, filed on Aug. 27, 1998, which is a continuation-in-part of application No. 29/060,518, filed on Sep. 30, 1996, now Pat. No. Des. 397,626.

The characteristic feature of our invention resides in the representation of the fractions on a measuring implement and their arrangements relative to their associated fractional line markers.

(51) **LOC (7) Cl.** **10-04**

FIG. 1 is a top plan view of a measuring implement in the form of a flat tape showing our design;

(52) **U.S. Cl.** **D10/74; D10/71**

FIG. 2 is a front elevational view of the implement shown in FIG. 1, the rear elevational view being identical;

(58) **Field of Search** D10/71, 74; 33/483-494

FIG. 3 is a left side elevational view of the implement shown in FIG. 1, the right side elevational view being identical;

(56) **References Cited**

FIG. 4 is a top plan view of an alternate embodiment of our design; and,

U.S. PATENT DOCUMENTS

FIG. 5 is a top plan view of yet another alternate embodiment of our design.
